DESIGN FOR A BOTTLE

Benjamin Lewis, New York, N. Y., assignor to Lionel Rothchild, Dallas, Tex.

Application April 12, 1946, Serial No. 128,538

Term of patent 14 years

(Cl. D58—8)

To all whom it may concern:

Be it known that I, Benjamin Lewis, a citizen of the United States of America, residing at New York, in the county of New York and State of New York, have invented a new, original, and ornamental Design for a Bottle, of which the following is a specification, reference being had to the accompanying drawing, forming part thereof.

In the drawing:

I claim:

The ornamental design for a bottle, as shown.
BENJAMIN LEWIS.
